[57] ABSTRACT

A board assembly mounts in a panel opening of a television receiver and includes wire receptacles for receiving antenna leads as well as a cable connector for coupling to a source of cable signals. A tuner cable extending to the television tuner section is supported on the board and is connected to the terminals of the cable connector. A switch mounted on the board controls the connection of broadcast signals from the wire receptacles through a balun transformer to the tuner cable. Each wire receptacle includes a spring terminal crimped to a wire and inserted into a housing, and the housing includes a movable wire release portion. The switch includes a pair of terminals crimped to wires and having compressible contact portions sandwiched together in a housing. A movable switch operator opens and closes the contacts and is detented in one position by the contacts.

SHEET 2 OF 2

ANTENNA BOARD ASSEMBLY WITH WIRE RECEPTACLE AND SWITCH

The present invention relates to an improved antenna board assembly for facilitating the interconnection of antenna and cable signals to the tuner section of a television receiver, and to improvements in wire receptacles and switches.

In many localities television signals are broadcast and are received by an antenna connected to a television receiver by antenna leads. In some instances, for example regions remote from transmitters and apartment house common antenna systems, signals are supplied by cable. In the past it has been difficult to adapt a television receiver for one or the other types of signals.

Typically, the VHF tuner of a television receiver is designed to receive unbalanced 75 ohm signals. However, many antenna leads for broadcast receivers supply balanced 300 ohm signals. Consequently, television receivers intended for broadcast transmissions customarily include a so-called balun transformer connected between the antenna terminals and the VHF tuner for transforming balanced 300 ohm signals to unbalanced 75 ohm signals. On the other hand, cable signals are normally unbalanced 75 ohm signals capable of being coupled directly to the VHF tuner. Adapting a particular receiver from one type of reception to the other normally requires a wiring change in the receiver or use of an additional coupling device or some other inconvenient modification. Similarly, when a television receiver is moved from place to place, the disconnection and connection of antenna leads from the commonly used screw terminals is an inconvenience.

In the manufacture of television receivers, typically connections are made between the tuner section, the balun transformer, and the antenna lead terminals. Further connections may be required if the receiver is designed to receive a cable signal. The mounting of these components and the making of the various connections using conventional soldering techniques involves substantial labor and expense.

Among the objects of the present invention are to provide an antenna board assembly substantially simplifying the fabrication of a television receiver; to supply an assembly containing all of the structure required for making either antenna lead connections or cable connections to the tuner section; to provide an assembly wherein the connection of wires to the various components is simplified; and to provide an assembly facilitating the adaptation of the receiver for broadcast and cable signals, and facilitating the connection and disconnection antenna wires.

In the use of screw terminals of the type often provided for connection of wires to television receivers and other devices, the terminal screw must be tightened by a tool over a stripped end of the wire or over a U-shaped terminal member, if one is supplied on the wire. In order to avoid this inconvenience, wire receptacles have been developed wherein the end of the wire is captured and contacted by a spring terminal. Examples of devices of this type may be found in U.S. Pat. No. 2,713,668 — Gibilisco and U.S. Pat. No. 2,720,634 — Hart. One major disadvantage of such devices is their complexity and cost. Another is that the conductive terminal must be touched to release a wire, resulting in some installations in a possible shock hazard.

Additional objects of the present invention are to provide an improved wire receptacle including an improved simple spring terminal; to provide a receptacle including a terminal precrimped to a wire and inserted into a housing; and to provide a wire receptacle having an improved wire release structure.

Many modern electrical devices and appliances make use of manually operated switches. Although many types of switches are known, it would be desirable to reduce costs by providing a switch having a minimum number of parts and characterized by great ease of assembly. Another object of the present invention is to provide such an improved switch.

In brief, the above and other objects and advantages of the present invention are achieved by the provision of an antenna board assembly including a board with panel mount means for attaching the assembly in a panel opening of a television receiver. The board is provided with wire receptacles including spring contacts for engaging inserted antenna lead wires. The board also includes a cable connector to which a source of cable signals may be coupled. Terminals of the cable connector are connected to conductors of a tuner cable extending from the board assembly to the television tuner section. Moreover, one of the cable terminals is provided with means for supporting the tuner cable.

In accordance with the invention, circuit means including a switch is coupled between the tuner cable and wire receptacles for controlling the interconnection of the antenna leads with the tuner cable. The circuit means includes a transformer, and transformer leads are attached by crimping to the spring terminals of the wire receptacles and to one of the switch terminals. The other switch terminal is crimped to a wire conductor leading to a terminal of the cable connector.

In accordance with another aspect of the present invention, there is provided an improved wire receptacle including a housing having a cavity with a wire engaging wall. A wire receiving opening extends from the cavity generally parallel to and aligned with the wall. A terminal is received in the cavity and has a base spaced from the wire engaging wall and a spring leg slanting away from the opening and inclined relative to the wall. An end of the spring leg abuts against the wall and serves to trap a wire between the spring leg and the wall. The housing includes a movable spring release means engageable with the spring leg for forcing the spring leg away from the wall to permit movement of the wire between the spring leg and the wall.

Another aspect of the invention relates to the provision of an improved electrical switch including a housing having a pair of spaced, interfacing support surfaces. A pair of terminals each include a compressible contact portion, and the contact portions are sandwiched between the walls in compression against one another. A switch operator is movable along a path extending between the contact portions to open and close the contacts.

The above and other objects and advantages of the present invention may be best understood from the following detailed description of an embodiment of the invention shown in the accompanying drawings, wherein:

FIG. 1 is a front elevational view of an antenna board assembly constructed in accordance with the invention;

FIG. 2 is a rear inverted elevational view of the assembly of FIG. 1;

FIG. 3 is a top view of the assembly of FIG. 1, with a portion in section, illustrating the manner in which the assembly is mounted in a television receiver panel opening;

FIG. 4 is a schematic diagram of the assembly of FIG. 1;

FIG. 5 is a somewhat simplified and diagrammatic exploded view of the assembly of FIG. 1 illustrating the manner in which various components of the assembly are interconnected;

FIG. 6 is an enlarged sectional view of the cable connector of the assembly taken along the line 6—6 of FIG. 2;

FIG. 7 is an enlarged sectional view of a wire receptacle of the assembly taken along the line 7—7 of FIG. 1;

FIG. 8 is a sectional view of the wire receptacle taken along the line 8—8 of FIG. 7; and

FIG. 9 is a side elevational view of one of the switch terminals of the assembly of FIG. 1.

Having reference now to the drawings, there is illustrated an antenna board assembly constructed in accordance with the principles of the present invention and designated as a whole by the reference numeral 10. The assembly 10 is designed to be mounted in an opening 12 of a panel 14 of a television receiver, only a fragment of which is shown in FIG. 3 of the drawings, and provides for simple and inexpensive interconnection of antenna leads and coaxial cable to the tuner section of the television receiver. The assembly 10 also makes possible convenient adaptation of the receiver for either broadcast or cable signals as well as convenient connection and disconnection of antenna leads.

In order to establish connections with sources of broadcast and cable television signals, the assembly 10 includes a VHF wire receptacle section generally designated as 16, a UHF wire receptacle section generally designated as 18, and a cable connector generally designated as 20. Associated with the cable connector 20 is a tuner cable supporting structure generally designated as 22 for supporting a tuner cable 24 adapted to extend to the television tuner section. A switch assembly generally designated as 26 controls the coupling of the VHF wire receptacle section 16 to the tuner cable 24 through a transformer 28.

Proceeding now to a more detailed description of the board assembly 10, the assembly includes a board member 30 preferably formed a molded, electrically insulating material such as a polypropylene plastic or the like. This construction has the advantage of permitting much of the structure of the board assembly 10 to be formed integrally with the board member 30. In order to minimize the projection of structure of the board assembly 10 beyond the outer surface of the television receiver panel 14, the board member 30 includes a recessed face wall 32 surrounded by a rim 34. To support the board member 30 in the opening 12, the rim 34 terminates in a lip 36 adapted to overlie the board surface. When the board member 30 is pressed into the opening 12, a pair of flexible mounting ears 38 are deflected inwardly and then expand so that serrated gripping portions 40 engage the edges of wall 14 at the sides of the opening 12 to hold the board 30 in position as shown in FIG. 3.

Through the provision of the cable connector 20, the board assembly 10 is adapted to receive signals supplied by an external coaxial cable. Connector 20 includes a plug member 42 received in an opening 44 in the face wall 32 of board member 30. Connector 20 also includes a pair of cable terminals 46 and 48 supported by the plug member 42 and adapted to establish electrical contacts with an external cable attached in conventional fashion to the connector 20.

10 More specifically, the plug member 42 comprises a generally tubular body formed of insulating material and having an opening 44 extending axially along its length. A threaded end portion 50 of the member 42 is adapted to receive a conventional internally threaded cable connector collar, and the plug member 42 includes flats 52 for properly locating the member in the opening 44. Plug member 42 is inserted through the face wall 32 from the rear, and is held in place by means of three latching ears 54, 56 and 58 engageable 15 with a flange portion 60 of the member 42.

One important advantage of the assembly 10 of the present invention is that connections between the various components are not made by conventional soldering, staking or other techniques. Rather, each of the 25 terminals associated with the assembly 10 includes wire crimping portions adapted to be precrimped to wires prior to being assembled with the board assembly to the end that a substantial savings in labor cost is achieved. This is true of the cable terminals 46 and 48.

30 With reference first to the cable terminal 46, this terminal comprises a stamped sheet metal part including a spring socket contact portion 62 extending from a shank portion 64 and receivable within the opening 44 in the plug member 42 for making electrical contact with the pin portion of a conventional coaxial cable connector. Resilient locking tabs 66 and shoulder portions 68 serve to lock the terminal 46 in position within the opening 44 as best shown in FIG. 6. Pairs of crimping flanges 70 and 72 are provided for crimping to 40 wires and conductive sleeves of electrical conductors.

50 Terminal 48 functions to provide an electrical connection with the grounded shield conductor of an external coaxial cable coupled to the cable connector 20. Terminal 48 is a stamped sheet metal part including an elongated shank portion 74 terminating at one end with a hook member 76 receivable in a recess 78 in the nose portion of the connector plug member 42. A slotted support arm 80 extends rearwardly from the plug member 42, and receives a rearward end portion 82 of the terminal 48. As can best be seen in FIG. 5, the terminal 48 is moved axially relative to the plug member 42 to insert the hook member 76 within the recess 78 and simultaneously to insert the end 82 through the support arm 80 where a resilient locking tab 84 engages the arm 80 to hold the terminal 48 securely in position.

55 In accordance with the invention, the board assembly 10 is provided with the support structure 22 for mounting the tuner cable 24. The terminal 48 is provided with two pairs of crimping flanges 86 and 88 crimpable onto the grounded shield conductor and outer insulation jacket of the cable 24 in order securely to hold the cable 24 and to complete a ground connection from the terminal 48 to the ground conductor of the cable 24.

60 One important aspect of the present invention relates to an improved wire receptacle structure best illustrated in FIGS. 1, 7 and 8. In the illustrated arrangement, the improved wire receptacle structure is utilized

in connection with the VHF and UHF wire receptacle sections 16 walls 146 18 of the board assembly 10. However, it will be apparent that features of the wire receptacle are useful in many environments.

Sections 16 and 18 are substantially identical with one another except in the manner in which they are interconnected with other components of the board assembly 10 and with a television receiver. Consequently, the UHF wire receptacle 18 is described in detail below, and similar reference numerals are used for the VHF section 16.

In general, the wire receptacle 18 of the present invention includes a housing generally designated as 92 defining a pair of similar cavities 94 each receiving an improved spring terminal member 96. A wire receiving opening 98 communicates with each cavity 94 for receiving a wire which is contacted and held in place by the spring terminal member 96. Housing 92 includes a wire release structure 100 for compressing the spring terminal 96 to free an inserted wire without the necessity for manual contact with the spring terminal 96 or other electrically conductive structure. In accordance with the invention, each spring terminal 96 is pre-crimped to a wire conductor. Although in the illustrated arrangement the housing 92 of each wire receptacle is integral with the board member 30 of the board assembly 10, it should be understood that for other uses the housing 92 could be an independent structure.

Each cavity 94 of the housing 92 is defined in part by a wire engaging wall 102 extending from the face wall 32 of the board member 30. The wire receiving opening 98 extends through an end wall 104 in a direction parallel to and aligned with the inner surface of the wire engaging wall 102. Preferably opening 98 is provided with a sloped, wire guiding mouth entrance facilitating the entry of a wire into the cavity 94 and along the wire engaging wall 102.

Each cavity 94 is further defined by a lower wall 108 opposite the wire engaging wall 102 and by a pair of side walls 110. In view of the fact that each housing 92 includes two cavities 94, the central side wall 110 is common to both cavities. Each lower wall 108 includes a slot 112 defining a locking shoulder 114 while each side wall 110 includes a recess 116 for positioning the spring terminal 96 within the cavity 94.

With reference now to the structure of the spring terminals 96, each terminal 96 includes a generally flat base portion 118 flanked at both sides by a side flange 120. As the terminal 96 is inserted into the cavity 94 through an aperture 122 in the wall 32, the side flanges 120 enter the recesses 116. The recesses assure that the terminal 96 is inserted in the proper orientation, and moreover engagement of the flanges 120 with the forward ends of the recesses 116 prevents over-insertion of the terminal. Flanges 120 also assist in preventing bunches of terminals 96 which have been precrimped to wires from becoming tangled with one another.

In order to hold terminal 96 in place, base 118 is provided with a resilient locking tab 124 which upon full insertion snaps into place against the locking shoulder 114 as best shown in FIG. 7. If removal of the terminal is necessary, this can be accomplished by insertion of a suitable tool into the slot 114 to depress the locking tab 124. Each terminal 96 also includes pairs of wire engaging crimping flanges 126 and 128 for crimping to the wire portion and the insulation portion of a wire conductor.

In accordance with the invention, the terminal 96 includes a spring leg 130 in the form of a folded over extension of the base 118. As best appears in FIG. 7, the spring leg slants away from the wire receiving opening 98 and is inclined relative to the wire engaging wall 102. The outermost edge of the leg 130 normally abuts in resilient contact against the wire engaging wall 102.

In order to depress the spring leg 130 relative to the wall 102, the wire release structure 100 is provided. In accordance with a feature of the invention, the structure 100 is integral with the housing 92, and includes a shelf member 132 extending from the wall 32 parallel with and spaced above the wire engaging wall 102. Projections 134 depend from the shelf member 132, one above each side of each cavity 94. In order to permit entry of the projections into the cavities 94, a slot 136 is formed in each wall 102 directly below the corresponding projection 134. In the illustrated arrangement where two side-by-side cavities 94 are provided, a common shelf member 132 is used and supports four of the projections 134.

The material of shelf member 132 is somewhat flexible and resilient permitting the shelf member 132 to be deflected downwardly by pressing with the finger. In order to permit movement of a wire between the spring leg 130 and the wire engaging wall 102, the shelf member 132 is depressed to move the projections 134 through the slots 136 and against the spring leg 130. Excessive depression of the spring legs 130 is prevented by engagement of a lip portion 138 of the shelf member 132 against the top of the wall 102, and the lip is contoured to have a firm flat engagement upon contact. When the receptacle 18 is used with relatively fine wires, such as antenna lead wires, the spring leg 130 is depressed both for insertion and withdrawal of the wires. With stronger wires, it may be possible for the wire itself to provide the force required to deflect the spring leg 130. After insertion of the wire, withdrawal is prevented because a wedging action results from the inclined orientation of the spring leg 130. Moreover, the angularly related edge of the spring leg 130 bites into the surface of an inserted wire to provide both firm holding and good electrical contact.

Another feature of the wire receptacle of the present invention arises from the shape and positioning of the projections 134. When relatively fine wire is used, it might be possible for the wire to become bent or distorted upon insertion so that it is not properly positioned between the spring leg 130 and the wire engaging surface 102. However, when the shelf member 132 is depressed, the two projections 134 enter the cavity 94 and are positioned at both sides of the wire receiving opening 98. Thus, an inserted wire is guided between the projections 134 and into the proper position.

Turning now to a description of the switch assembly 26 of the present invention, the switch assembly functions in connection with the board assembly 10 to control the interconnection of the VHF wire receptacle section 16 by way of the transformer 28 with the tuner cable 24. Important features of the present invention are embodied in the structure of the switch assembly 26, and it should be understood that the assembly is adaptable to many situations where a simple, inexpensive and easily assembled switch is desirable.

In general, the switch assembly 26 includes a housing 140 which in the illustrated arrangement is unitary with the board member 30. In other arrangements, the hous-

ing 140 could be independent. Supported within the housing 140 are a pair of switch terminals 142 adapted to be precrimped to wire conductors. The switch is operated between open circuit and closed circuit conditions by means of a switch operator 144 movable along a path extending between the terminals 142.

More specifically, the housing 140 includes interfacing side walls 146 and 148 and interfacing top and bottom walls 150 and 152 extending from the face wall 32 of the board member 30 and defining a cavity 154 within the housing 140. The side walls 146 and 148 are each provided with a slot 156 defining a locking shoulder 158, and, as appears in FIG. 2, side walls 146 and 148 may include thickened central portions for this purpose. Slots 156 extend to the front surface of the face wall 32 in order to simplify coring of the slots and to permit removal of the switch terminals 142 with a suitable tool. Each side wall 146 and 148 also is provided with an abutment 160 for limiting insertion of the terminals 142.

In accordance with the invention, the terminals 142 each include a resilient contact portion 162 performing a dual function and thereby simplifying the structure of the switch. When the terminals 142 are inserted into the cavity 154 as best shown in FIG. 3, the terminals are sandwiched between the side walls 146 and 148 and are pressed against one another. Due to this compression, the resilient contact portions 162 assist in holding the switch terminals 142 in position. In addition, the resilient contact portions 162 engage the switch operator 144 in the open circuit condition of the switch in order to provide a detent action.

Referring now more specifically to the structure of the terminals 142, one of which is illustrated in detail in FIG. 9, each terminal comprises a stamped metal part in the form of a metal strip having a looped end comprising the resilient contact portion 162. More particularly, the terminal includes a base portion 164 adapted to lie against the corresponding side wall, a first folded over portion 166, and a second folded over portion 168 slidingly in engagement with the base portion 164. Consequently, the base 164 and the portions 166 and 168 form a loop closed upon itself providing resilience of the contact portions 162 due to deflection of the portions 166 and 168 and sliding of the portion 168 along the base 164.

Each terminal includes pairs of flanges 170 and 172 for crimping respectively to the wire and to the insulation of wire conductors. After attachment to wires, the terminals are inserted into the cavity 154 until their nose portions strike the abutments 160. The base 164 of each terminal is provided with a resilient locking tab 173 engageable with the corresponding locking shoulder 158 to secure the terminal in position.

In order to provide for manual opening and closing of the switch assembly 26, the operator 144 includes a shank portion 174 slidably received in an opening provided in a boss 176 formed for this purpose on the face wall 32. The accessible end of the shank 174 is provided with a manually engageable button element 177 for pushing and pulling the shank 174 between positions. Withdrawal of the shank 174 from the cavity 154 is prevented after initial insertion by means of a resilient locking tab 178 engageable with the wall 132 within the cavity 154.

As noted above, one function of the resilient contact portions 162 is to provide a detent action. For this pur-

pose, the shank 174 is provided with a neck portion or recess 180. When the button 177 is pushed to force the shank 174 between the switch terminals 142, the neck 180 is resiliently grasped by the contact portions 162 to detain the operator 144 in the open circuit position of the switch. Further insertion is prevented by engagement of button 177 with the boss 176. When this detaining force is overcome by pulling of the button to the position illustrated in FIG. 3, the contact portions 162 engage one another to close the circuit between the switch terminals 142. If desired, the intercontacting surfaces may be coated with a permanent highly conductive material such as gold. A detenting action is provided in the open circuit position due to the locking tab 178 and due to the force required to insert the shank 174 between the terminals 142.

As a result of the use of precrimped terminal members for the wire receptacles, the switch assembly, and the cable connector, the board assembly 10 of the present invention offers substantial savings in the fabrication cost of television receivers. In order to complete the assembly, the above described components are interconnected to the television receiver in the manner illustrated schematically in FIG. 4 and physically in FIG. 5. The balun transformer 28 is of a conventional type well known to those skilled in the art and includes a core 182 having an array of windings thereon in a standard pattern. Extending from the windings are a group of ground leads 184 as well as a pair of leads 186 and 188 adapted to receive a balanced 300 ohm broadcast signal. Also extending from the transformer 28 are a pair of leads 190 and 192 adapted to be connected in common and to provide an unbalanced 75 ohm signal relative to ground. In fabrication of the assembly 10, the spring terminals 96 of the VHF wire receptacle section 16 are crimped to the transformer leads 186 and 188. Similarly the transformer leads 190 and 192 are crimped together to one of the switch terminals 142. As indicated in FIG. 5, the switch terminal 142 and the spring terminals 196 are then inserted into the switch assembly 26 and into the wire receptacle section 16 respectively.

The tuner cable 24 is of conventional construction and includes a central wire conductor 194 surrounded by and insulated from a ground shield conductor 196. The cable 24 is mounted to the cable terminal 48 in the manner described above, and the ground leads 184 of the transformer 28 are captured beneath the crimping flanges 88 and 86 of the terminal 48 as shown in FIGS. 5 and 6 in order to complete a connection between the transformer and the cable conductor 196. The cable terminal 46 of the cable connector 20 is attached by crimping to the lead 194 of the tuner cable 24, and also to one end of an additional wire conductor 200. The opposite end of wire conductor 200 is crimped to the other switch terminal 142. The preattached terminals 142, 46 and 48 are then assembled with the assembly 10 as indicated by broken lines in FIG. 5.

Having reference now to the reception of UHF broadcast signals, these are normally received through antenna leads at the proper impedance level for the UHF tuner. Consequently, a pair of wires 202 and 204 are crimped to the spring terminals 96 of the receptacle section 18 prior to insertion of the terminals into the receptacle section 18. As indicated in FIG. 4, the wires 202 and 204 may lead directly to the UHF tuner of the receiver.

In addition to providing substantial advantages in fabrication, the board assembly 10 of the present invention adds to the versatility of a television receiver and makes the use of the receiver far more convenient than with known structures. The user of the receiver may adapt the same for either broadcast or cable transmission simply by operation of the switch assembly 26. More specifically, the cable connector 20 is always interconnected with the tuner cable 24, so that the receiver may be used with a cable signal simply by connecting an external cable to the connector 20. On the other hand, when it is desired to receive broadcast transmissions, antenna leads are simply received within the wire receptacle sections 16 and 18, and the switch assembly 26 is operated to the closed position in order to couple broadcast VHF signals through the transformer 28 to the tuner 24.

While the present invention has been described with reference to details of the illustrated embodiment, it should be understood that these details do not limit the invention as defined in the following claims.

We claim:

1. A wire receptacle comprising a housing having a cavity defined in part by a relatively rigid wire engaging wall, a wire receiving opening extending from said cavity generally parallel to and aligned with said wall, a terminal in said cavity having a base spaced from said wall and having a spring leg slanting away from said opening and inclined relative to said wall, said spring leg having an end spaced from said base and abutting said wall, and resilient spring release means being unitary with a portion of said housing for engaging said spring leg and forcing said spring leg away from said wall in order to permit movement of a wire between said end of said spring leg and said wall.

2. The wire receptacle of claim 1, said terminal further including a conductor engaging portion adapted to be attached to a conductor.

3. The wire receptacle of claim 1, said spring release

means being integral with said housing.

4. The wire receptacle of claim 1, said housing including a second wall spaced from and interfacing said wire engaging wall, said terminal base lying against said second wall and said spring leg biasing said base against said second wall, and locking means on said base and second wall for holding said terminal in said cavity.

5. The wire receptacle of claim 4, said terminal further including a pair of side flanges extending from said base toward said wire engaging wall, and stop means on said housing within said cavity engaged by said side flanges for preventing over-insertion of said terminal into said cavity.

10 6. A wire receptacle comprising a plastic housing having a cavity defined in part by a base wall, said housing including a relatively rigid wire engaging wall extending from said base wall, a wire receiving opening extending from said cavity generally parallel to and aligned with said wire engaging wall, a terminal in said cavity having a spring leg slanting away from said opening, spring release means supported by said housing for engaging said spring leg and forcing said spring leg from said opening, said spring release means including a deflectable shelf member extending from and unitary with said base wall outside of said cavity spaced from and generally parallel to said wire engaging wall, projection means on said shelf member extending toward said wire engaging wall, and aperture means in said wire engaging wall aligned with said projection means and with said spring leg.

20 7. The wire receptacle of claim 6, said projection means comprising a pair of elongated projections generally parallel to the desired direction of a received wire and spaced apart a distance greater than the width of the wire, and said aperture means comprising a pair of slots extending from a region adjacent the wire receiving opening.
